UNITED STATES PATENT OFFICE

FRED M. YOUNG, OF RACINE, WISCONSIN

MULTIPLE UNIT SPACE HEATER

Application filed August 21, 1929. Serial No. 387,361.

The main objects of this invention are to provide improved means for combining a plurality of individual space heaters of the type shown in my copending application Serial No. 358,872, filed April 29, 1929, which has now matured into Patent No. 1,753,587, granted April 8, 1930, in a single heating unit; to provide improved means for selectively proportioning the supply of air to a 10 multiple heating unit of this kind from the exterior and interior of a building; to provide means for distributing the flow of air from the interior of the building to the heating unit, between the top and bottom ends of 15 the unit so as to obviate the creation of concentrated and unhealthy drafts; to provide a plurality of individual space heaters in a heating unit of this kind, each of which may be selectively rendered inoperative for purposes of repair or to reduce the heating capacity of the unit without effecting the other 20 space heaters.

An illustrative embodiment of the invention is shown in the accompanying drawings, 25 wherein:—

Figure 1 is a top plan partly in section of a multiple unit heater.

Fig. 2 is a front elevation.

Fig. 3 is an end elevation partly in section.

Fig. 4 is an end elevation of one heating and ventilating unit, a plurality of which are used in the improved apparatus.

Fig. 5 is a fragmentary vertical section of the top wall of the heater taken on the line 30 5—5 of Fig. 1.

Fig. 6 is a detail illustrating means for adjusting shutters for controlling the air supply to the heaters.

In the form shown the heater includes a 40 casing having spaced apertures in registration with which are mounted unitary heating and ventilating units of the type shown in my copending application, Serial No. 358,872, filed April 29, 1929. An inlet duct communicates with the interior of the casing at its rear side and with the atmosphere exterior of a building, and the bottom of the casing is open. The top of the casing has a sectional wall which may be partly or completely 45 removed.

In the construction illustrated the heater includes a cabinet 1 formed of sheet metal and having upright legs 2 which support it above the floor. An air outlet is formed in each end wall of the casing and a pair of air 55 outlets are formed in the front wall of the cabinet 1. The bottom of the casing is open and the top is provided with a wall comprising longitudinal sections 3 in the form of channel members having flanges 4 and 5 60 in which registered apertures are formed and which are detachably secured together by bolts 6. The rear wall of the cabinet has an inlet 7 communicating with an inlet duct 8 which extends through a passage 9 in a vertical wall 10 of a building. The external end of the duct 8 is provided with adjustable shutters 11 by means of which the duct may be completely or partially closed if desired. The shutters 11 are pivoted at their upper 70 ends and are pivotally connected together by a link 32, and the shutters are adjusted as a unit by means of a handle 33, Fig. 6, which is fast to a rod 34 having an arm 35 connected by a link 36 to the shutters. 75

A pair of heating and ventilating units 12 is mounted on the end walls of the cabinet by a supporting frame 13, each unit being in registration with the outlet in one end wall. Mounted on the front of the cabinet 1 is a 80 pair of similar unitary heating and ventilating members 14, each secured to the cabinet in registration with one of the outlets of the front wall by brackets 15 and a supporting frame 16.

The heating and ventilating unit illustrated in Fig. 4 includes upper and lower header tanks 17 and 18 respectively which are connected by a heat interchanger core 19 comprising heating medium tubes 20 and transverse fins 21. The heat transfer core is enclosed by side plates 22 extending between the upper and lower header tanks and it is connected with a boiler or other suitable heating means, not shown, by a supply pipe 23 and a discharge pipe 24 on the upper and lower header tanks 17 and 18 respectively. Each supply pipe 23 is provided with a valve 25 by means of which the flow of heating medium to each unit may be selectively con-

trolled. The drain pipes 24 of each unit may be connected with a return pipe when hot water is used as a heating medium.

A blower motor 26 is secured to the upper header tank of each unit by a supporting arm 27 which extends into the cabinet 1 through the respective outlets in the side and front walls thereof. The motor 26 carries a blower member 28 in the form of a fan propeller which is designed to extract air from the interior of the cabinet 1 and discharge it through the heat interchanger into the interior of a building. Baffle plates or partitions 29 are arranged in the cabinet 1 between adjacent unitary heating and ventilating units for preventing confliction between the currents of air extracted by the blowers of the respective heating units and the creation of eddy currents. These partitions extend from the front wall of the casing substantially to the middle thereof, and are supported at their inner edges by vertical bars 30. Each blower motor 26 is provided with an individual switch, by means of which any desired heating and ventilating units may be rendered inoperative without affecting the other units.

Air deflectors 31 are adjustably mounted on the heating units for distributing the currents of heated air in desired directions.

In operation, when the valves 25 are open and the blowers 28 are driven, currents of warm air are impelled outwardly from the casing through the outlets and through the heat interchangers with which the respective outlets register. When the top of the cabinet and the shutters 11 of the inlet duct are closed the discharge of air through the outlets causes an inrush of air at the bottom of the cabinet. If the flow of the air toward the bottom of the cabinet is too great, it may be reduced by either removing one or more of the sections 3 of the top wall of the cabinet or by opening the shutters 11 on the inlet duct. In either event the flow of air to the casing will be divided and the intensity of the draft at the bottom of the cabinet will be proportionately reduced. At certain times of the year it is advantageous to recirculate the air in the building through the heater without admitting much fresh air from the outside of the building; while at other times it is desirable to provide a mixed supply of fresh and previously circulated air. The heater may be conditioned to admit the desired amount of fresh air by adjustment of the shutters 11 and it may readily be adapted for dividing the flow of previously circulated air into two currents by removing one or more of the sections 3 of the top wall.

Each ventilating and heating unit is independent of the other units, and may be shut down during repair or to reduce the heating and ventilating capacity of the heater without effecting the other units. Selected

units may be operated while other units are not in use for directing currents of heated air toward occupied portions of the building, thereby obviating the waste of heat.

Although but one specific embodiment of this invention has been herein shown and described, it will be understood that details of the construction shown may be altered or omitted without departing from the spirit of this invention as defined by the following claims.

I claim:

1. Heating apparatus of the class described comprising a casing having a pair of air outlets therein, an air inlet duct for conveying fresh air to said casing from the exterior of a building in which the casing is located, the bottom of said casing being open for admitting air from the interior of said building, and a pair of unitary space heaters each comprising a heat interchanger and means for withdrawing air from said casing and discharging it through said heat interchangers, and shutters on said inlet duct for proportioning the admission of air into said casing between the lower open end thereof and said duct.

2. Heating apparatus of the class described comprising a casing having a pair of air outlets, the lower end of said casing being open for admitting air from the interior of a building, a pair of unitary space heaters, each mounted on said casing in registration with one of said air outlets and each comprising a heat interchanger, a separate blower for each space heater for withdrawing air from said casing and discharging it through said heat interchanger, and a cover on the top end of said casing comprising removable sections for admitting air through the top of said casing and reducing the draft at the bottom thereof.

3. A multiple unit heating apparatus comprising a casing having a plurality of air outlets therein, a plurality of heating units mounted on said casing, one in registration with each of said outlets and comprising a blower, said heating units each being connected with a heating medium supply pipe, and means associated with each unit respectively for independently controlling the supply of heating medium to each unit.

4. A multiple unit heating apparatus comprising a casing having an open end and a plurality of air outlets therein, an inlet duct communicating with said casing for supplying fresh air from the exterior of a building to said casing, means on said duct for controlling the supply of air from the exterior of said building to said casing and the flow of air from within said building to the bottom of said casing, a plurality of heating units mounted on said casing, each comprising a blower in registration with one of said outlets and a heat interchanger, means for

connecting said heat interchangers with a heating medium supply system, and means for independently controlling the circulation of heating medium through said respective heat interchangers.

⁵ Signed at Chicago this 19th day of August, 1929.

FRED M. YOUNG.
